(57) **CLAIM**

I claim the ornamental design for a combined pair of aircraft wings and stub wings, as shown and described.

DESCRIPTION

FIG. 1 is a side view of a combined pair of aircraft wings and stub wings, a side view of the reverse side is a mirror image of the illustrated side;

FIG. 2 is a front view of the aircraft with the two stub wings and the two wings combination;

FIG. 3 is a rear view of the aircraft with the two stub wings and the two wings combination;

FIG. 4 is a top view of the aircraft with the two stub wings and the two wings combination; and,

FIG. 5 is a bottom view of the aircraft with the two stub wings and the two wings combination.

The broken lines shown in the drawings illustrate portions of the aircraft that do not form part of the claimed design.
